UNITED STATES PATENT OFFICE.

CHARLES C. HANSEN, OF FOREST PARK, ILLINOIS, ASSIGNOR TO REFRIGERATOR SPECIALTIES COMPANY, OF CHICAGO, ILLINOIS, A CORPORATION OF ILLINOIS.

REFRIGERATING APPARATUS.

1,259,014.

Specification of Letters Patent. Patented Mar. 12, 1918.

Application filed February 23, 1916. Serial No. 79,814.

To all whom it may concern:

Be it known that I, CHARLES C. HANSEN, a citizen of the United States, and a resident of Forest Park, in the county of Cook and State of Illinois, have invented certain new and useful Improvements in Refrigerating Apparatus, of which the following is a full, clear, and exact description.

The invention relates to refrigerating apparatus and more particularly to mechanism for automatically controlling the operation of the system, responsively to variations in temperature in the room or compartment to be refrigerated.

In automatic refrigerating systems, in which a cooling liquid for the refrigerant condenser or the compressor is used, it has been found that the operation of the refrigerant compressor, when the supply of cooling liquid is insufficient or fails, is destructive to the apparatus. One object of the present invention is to provide improved controlling mechanism for the apparatus, controlled by the supply of cooling water, and in which provision is made for automatically setting the starting mechanism in position to become operative automatically to re-start the compressor when the supply of cooling-liquid is restored.

A further object of the invention is to provide improved controlling mechanism for automatic refrigerating systems.

The invention consists in the several novel features hereinafter set forth and more particularly defined by claims at the conclusion hereof.

In the drawings: Figure 1 is a vertical section of the improved controlling mechanism, parts being shown in elevation. Fig. 2 is a section taken on line 2—2 of Fig. 1. Fig. 3 is a section taken on line 3—3 of Fig. 1. Fig. 4 is a horizontal section taken on line 4—4 of Fig. 3. Fig. 5 is a vertical section showing the connection between the stem of the water-valve operated by the motor and its connection for operating the switch-lever for controlling the restarting mechanism. Fig. 6 is a detail section through the cams on the shaft operated by the starting-motor, for operating the water-valve and the switch for controlling the operation of the compressor-motor, respectively. Fig. 7 is a detail of the cam for operating the switch for controlling the motor which operates the compressor. Fig. 8 is a detail of

the cam for operating the water-valve. Fig. 9 is a diagram of a refrigerating apparatus and the improved controlling mechanism, the parts being shown in normal position. Fig. 10 is a diagram of the circuit-controller in position assumed between the starting and stopping cycles of the starting-motor. Fig. 11 is a view of the circuit-controller in position assumed when the water supply in the condenser fails and after the controller has been operated by the starting-motor to cause the compressor and motor to restart upon the restoration of the water-supply.

Referring to the diagram (Fig. 9) *a* denotes a pump or compressor for the refrigerant; *b*, a refrigerant-line suitably connected to the pump; *c*, a condenser-coil in a tank *d*; *e*, a receiver for the refrigerant; 17, a motor for driving the compressor; and 16 a pipe which supplies cooling water to the refrigerating system and is connected to the tank *d*.

Motor 17 is connected to be supplied with current from a pair of line-conductors 18 and 19. A switch comprising contacts 20 and 21 and a lever 22 is included in a conductor 19^b which connects one brush of the motor to line-conductor 19. The other brush of this motor is connected to line-conductor 18 by a branch-conductor 18^a.

A starting motor 23 is employed to operate a valve 52 for controlling the water supply to the condenser, the switch-lever 22 for controlling the operation of the motor 17, and a circuit controller 30, and is suitably mounted upon a bracket 34 which is adapted to be secured to some suitable, convenient support of the system. A hood 35 incloses said motor and its associated parts. Controller 30 is secured to shaft 41, which is driven by motor 23 through a gear-train comprising a worm 36 on the motor-shaft and meshing with a gear 37 on an upright shaft 38, a worm 39 on shaft 38 and meshing with a suitable gear 40 fixed to the shaft 41. Shaft 41 is mounted in bearings 45 and 46.

A cam 76 on shaft 41 operates a vertical slide 73 carrying a roller 73^a. The lower end of this slide bears against a lever 74 which is pivoted, as at 75, to support 58. This lever is pressed upwardly by a spring 80 held in a slotted housing 80^a and has its distal end pivotally connected to an arm 110

77 which is pivoted to a lug 79 at 78. A link 81 pivoted to switch-lever 22, at 82, is 5 slidable longitudinally in the hub of arm 77. A head 83 on the lower end of link 81 acts as a one-way stop between link 81 and arm 77. A spring 84, coiled around link 81, is interposed between the hub of arm 77 and the upper end of said link.

Shaft 41 is operated in cycles of one-half 10 revolution each, to alternately start and stop motor 17 and the operative portion 76^a of cam 76 is disposed to close switch-lever 22 during the latter portion of the starting cycle and to hold it closed between the 15 starting and stopping cycles.

This device exemplifies a spring-pressed connection operated by the starting-motor for shifting the switch for controlling the operation of the motor 17 which drives the 20 compressor.

A supply-pipe 50 for cooling water is connected to a valve-casing 51, and pipe 16, for conducting water to the condenser, is connected to the outlet in this casing. This 25 valve casing is formed with a bracket 58 which is secured to the underside of a supporting bracket 34 to support the valve-casing in convenient relation to the starting mechanism. At the inlet side of this casing, 30 a valve 52 which is normally closed by a spring 53, controls the flow of cooling water from the supply pipe 50 to the pipe 16. The stem 54 of valve 52 extends upwardly through a packing box 55 in the casing 51 35 and carries a roller 56 which is adapted to be operated by a cam 57 fixed to a shaft 41. This cam 57 (Fig. 3) is formed to open valve 52 during the initial portion of the starting cycle of the motor, to close the 40 valve during the latter portion of the stopping cycle and to hold the valve open between the starting and stopping cycles of shaft 41.

The pressure of water in transit to the 45 pipe 16 in a chamber 59 in casing 51 controls a plunger 60 which is slidably mounted in casing 51 at one side of the valve 52. The upper side of this plunger is exposed to the water-pressure in chamber 59. A 50 spring 62 serves to lift the plunger and to hold it normally raised with force slightly less than the minimum pressure required for the condenser. Plunger 60 has openings 63 to register with the outlet-duct 64 55 leading to the pipe 16. A screw 66 engaging a cap 67 on the lower end of spring 62 is adapted to adjust the force of this spring according to the pressure required in the 60 operation of the condenser. If the water supply fails or is below the minimum pressure necessary for proper operation of the condenser, plunger 60 will remain in the 65 position shown in Fig. 1 and keep the outlet to pipe 16 closed. When water from pipe 50 is under sufficient or normal pres-

sure, it will force plunger 60 downwardly against the force of spring 62 to bring ports 63 into position to cause water to flow through the casing 51 to the condenser as long as valve 52 is held open. When valve 70 52 is closed, spring 62 will restore plunger 60 to its normal position, it being understood that there will be a slight leakage between the plunger 60 and the cylinder 61, so that the water above the plunger 60 75 can escape to pipe 16. This device exemplifies controlling means operated by the cooling liquid for controlling circuit connections for the starting-motor.

Plunger 60 is secured to a stem 69 which 80 extends through a packing-box 71 in a head 70 in the casing 51, and the upper end of this stem is provided with a nut or abutment 72 for operating a circuit-controlling lever 103. This lever 103 is adapted to 85 bridge across contacts 101 and 102 to control a circuit for operating the starting-motor when the pressure of water is sufficient for the condenser, and to bridge across another pair of contacts 99, 100 to control a circuit 90 for operating the starting-motor, if the supply of water is insufficient or fails. The connection between stem 69 and lever 103 comprises a lever 105 which is pivoted to support 34, as at 106, and to which a spring 95 104 is applied to yieldingly hold the lever raised, and a link 107 pivoted to lever 105 and to an arm 108 on lever 103. Stem 69 is slidably held in a collar 109 on a stud 110 (see Fig. 5), extending through a slot 111 100 (see Fig. 3) in lever 105. When valve 52 is open, spring 104 will tend to operate lever 105 and switch lever 103 into position to close a circuit at contacts 99, 100 and stem 69 of plunger 60 will, responsively to 105 the water pressure, overcome the force of spring 104 and retain lever 103 in position to close a circuit 101, 102 (full lines Fig. 3). When valve 52 is closed, switch-lever 103 will be held in said position by a lever 110 112 (Figs. 4 and 5), which is pivoted to a stationary stud 113, and has one of its ends disposed to be lifted by an abutment 114 on the stem 54 of valve 52 and its other end disposed to engage an abutment 115 115 on lever 105. When valve 52 is opened, lever 112 is released so that spring 104 may shift levers 105 and 103 into the position indicated in dotted lines in Fig. 3 under control of plunger-stem 69. This shift 120 occurs only when the water-supply fails or is insufficient to cause nut 72 on the stem of plunger 60 to hold lever 105 downwardly against the force of spring 104.

An annular contact-support 48 is secured 125 to support 34 in associated relation with the controller 30 on shaft 41. Spring-contacts 32, 33 and 94, preferably in the form of spring-pressed radially slidable supports and rollers, are mounted for limited move- 130

ment in and insulated from support 48. A spring-pressed shifter 97, carrying a roller adapted to be operated by the controller 30, is also slidably mounted in support 48 and its outer end is adapted to operate a resilient switch 96, which is normally in engagement with the outer end of contact 94. Shifter 97 is insulated from member 96. Controller 30 is provided with a notch 30^a for cutting out either of the contacts operating thereon and with a cam 31 for operating the shifter 97.

The starting motor 23 is included in a conductor 27 which is connected to the line-conductor 18 and to contacts 100 and 101. A conductor 27^a connects contact 102 and a thermostat-contact 28. Contact 32 is connected to said conductor. A conductor 98 connects switch-member 96 and contact 99. Contact 33 is connected to the thermostat 24 by a conductor 33'. Contact 94 is connected by a conductor 25 to the line-conductor 19 and to the thermostat-contact 26.

A fuse 19^a (Figs. 1 and 9) is included in conductor 19^b which extends from line-conductor 19 to the switch contact 20. A switch consisting of an arm 92 and an arcuate-contact 91 is included in a conductor 90 which is connected to conductor 19^b so as to cut out the fuse. Switch-arm 92 is operated by member 92^a on shaft 41 which is operated by the starting-motor 23. When this switch is closed, the fuse will be short-circuited and current will be directly supplied to the motor 17. This cut-out switch is adapted to cause this to occur during the initial operation of motor 17 or for a period of sufficient length to enable the motor to start the compressor before the fuse 19 is cut into the circuit. During the remainder of each operation, said switch will be open to render the fuse operative. This device exemplifies a fuse cut-out for the compressor motor which is controlled and operated by the starting motor.

When the compressor is at rest, the controlling mechanism will be in the position shown in Figs. 1 and 9. When the temperature of the refrigerating room or space rises sufficiently to require operation of the system, the thermostat 24 will move against contact 26, whereupon a circuit for the operation of motor 23 will be established as follows: line-conductor 18, conductor 27, in which motor 23 is included, contact 101, lever 103, contact 102, conductor 27^a, contact 32, controller 30, contact 33, conductor 33', thermostat 24, contact 26, conductor 25 and line-conductor 19. This circuit will cause the motor 23 to operate shaft 41 a cycle of one-half revolution or until the controller 30 has been rotated a one-half revolution, at which time this circuit will be interrupted between contact 32 and the controller 30, as shown in Fig. 10. During the initial

portion of this cycle of shaft 41, the water-valve 52 will be opened by cam 57. If the water pressure is sufficient, plunger 60 will operate stem 69 and abutment 72 to hold switch 103 in its normal position across contacts 101 and 102, after stop 114 releases lever 112. Toward the end of this cycle, switch-lever 22 will be shifted by cam 76 to close a circuit for motor 17 for driving the compressor, as follows: line-conductor 18, conductor 18^a, motor 17, conductor 19^b, switch-contact 21, lever 22, contact 20, conductor 90 in which the switch 91, 92, is included, and conductors 19^b, 19. Initially, and during a sufficient period for the motor 17 to start the load, this circuit, through switch 91, 92 will continue, but before the circuit for the motor 23 is interrupted at the end of a starting cycle, lever 92 will be opened by its connection 92^a with shaft 41 to cut in the fuse 19^a, and cause the current from contact 20 to pass to line-conductor 19 through said fuse. This permits the motor to start the compressor before the fuse is cut into the circuit.

When the motor 17 has been operated for a sufficient period to reduce the temperature in the refrigerating room to the predetermined minimum, thermostat 24 will engage contact 28, whereupon a circuit for operating the motor 23 and shaft 41 for a stopping cycle, will be established as follows: line-conductor 18, conductor 27, in which motor 23 is included, contact 101, lever 103, contact 102, conductor 27^a, thermostat-contact 28, thermostat 24, conductor 33', contact 33, controller 30, contact 94, conductor 25 and line-conductor 19. This circuit will remain until shaft 41 and controller 30 have been operated a half-revolution and the notch in the controller is adjacent the contact 94 when the last mentioned circuit will be interrupted. During this stopping cycle, cam 76 will be operated initially to permit switch-lever 22 to be opened by spring 80, and during the latter portion of this cycle, cam 57 will permit the water-valve to be closed by its spring 53. During the latter portion of this cycle, switch 90, 91 will pass into closed position to short-circuit the fuse 19. At the conclusion of this stopping cycle, controller 30 will break the circuit at contact 32, and the mechanism will be restored to normal position.

When valve 52 has been opened and stop 114 is lowered to release lever 112, which holds lever 105 and switch-lever 103 in the normal position shown in Fig. 9, and the pressure in the water line is insufficient to operate plunger 60 to cause abutment 72 to hold levers 105 and 193 in said position, spring 104 will shift lever 103 into position to bridge across contacts 99, 100, and, thereupon, a circuit for motor 23 will be established as follows: line conductor 18, 130

conductor 27 in which motor 23 is included, contact 100, lever 103, contact 99, conductor 98, spring-contact 96, contact 94, conductor 25 and line-conductor 19. This circuit will cause the starting motor to be operated independently of the thermostatic contacts 26, 28, and will remain closed until the controller 30 has moved the full starting cycle and a portion of the stopping cycle of shaft 41, that is, until cam 31 on controller 30 has been rotated into contact with the shifter 97, whereupon, the last mentioned circuit will be interrupted at contacts 94, 96, causing the motor 23 to stop with the controller in position shown in Fig. 11. During this operation, the switch-lever 22 will be closed and again opened, and the water-valve 52 will be opened and held open. The controlling mechanism will remain set in this position until the water operates the plunger 60, whereupon it will automatically start the motor 23 and complete the stopping cycle of shaft 41 and immediately cause its operation through the starting cycle to restart the motor 17. When plunger 60 shifts lever 103 into position shown in Fig. 9, as the result of the restoration of water-pressure, said lever will establish a circuit through motor 23.

The circuit will then be as follows: conductors 18, 27, contact 101, lever 103, contact 102, conductor 27^a, contact 32, controller 30, contact 94 and conductors 25 and 19, until the controller concludes the normal stopping cycle (Fig. 10). In lieu of stopping at the end of this cycle, the motor 23 will continue to operate because the thermostatic circuit through contact 26 will be closed, until a normal starting cycle has been completed (Fig. 10).

The controlling mechanism set forth exemplifies one in which the switch for the compressor-motor, operated by the starting motor and in which the water-supply for the condenser controls circuit connections for the starting motor, to automatically stop and restart the compressor-motor, and in which provision is made for automatically rendering said motor operative as soon as there is sufficiency of water supply.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a refrigerating system, the combination of a compressor, a motor for operating the compressor, a switch for controlling said motor, a starting motor, an operative connection between the starting motor and said switch, means for supply-

ing cooling liquid, and means controlled by the pressure of the cooling liquid for controlling the operation of the starting motor.

2. In a refrigerating system, the combination of a compressor, a motor for operating the compressor, a spring-closed switch for controlling said motor, a starting motor, an operative connection between the starting motor and said switch, means for supplying cooling liquid to the system, and means controlled by the pressure of the cooling liquid for controlling the operation of the starting motor. 70 75

3. In a refrigerating system, the combination of a compressor, a motor for operating the compressor, a switch for controlling said motor, a starting motor, an operative connection between the starting motor and said switch, comprising a cam and a lever, means for supplying cooling liquid to the system, and means controlled by the pressure of the cooling liquid for controlling the operation of the starting motor to operate said connection to open 80 85 90

4. In a refrigerating system, the combination of a compressor, a motor for operating the compressor, a switch for controlling said motor, a starting motor, a shaft driven by the starting motor, an operative connection between said shaft and said switch, means for supplying cooling liquid to the system, and means controlled by the pressure of the cooling liquid for controlling the operation of the starting motor. 95 100

5. In a refrigerating system, the combination of a compressor, a motor for operating the compressor, a switch for controlling said motor, a starting motor, an operative connection between the starting motor and said switch, means for supplying cooling liquid to the system, and means controlled by the pressure of the cooling liquid for controlling the operation of the starting motor to operate said connection to close and open the switch responsively to a deficiency in the supply of cooling liquid. 105 110

6. In a refrigerating system, the combination of a compressor, a motor for operating the compressor, a switch for controlling said motor, a starting motor, an operative connection between the starting motor and said switch, means for supplying cooling liquid to the system, and thermostatic and pressure-controlled means for controlling the operation of the starting motor to operate said connection to close and open the switch. 115 120

7. In a refrigerating system, the combination of a compressor, a motor for operating the compressor, a switch for controlling said motor, a starting motor, a shaft driven by the starting motor, an operative connection between said shaft and said switch, means 125 130

- for supplying cooling liquid to the system, and means controlled by the pressure of the cooling liquid, for controlling the operation of the starting motor to operate said connection to close the switch.
8. In a refrigerating system, the combination of a compressor, a motor for operating the compressor, a spring-closed switch for controlling said motor, a starting motor, an operative connection between the starting motor and said switch for opening the switch, means for supplying cooling liquid to the system, and means controlled by the pressure of the cooling liquid, for controlling the operation of the starting motor to operate said connection to close and open the switch.
9. In a refrigerating system, the combination of a compressor, a motor for operating the compressor, a switch for controlling said motor, a starting motor, an operative connection between the starting motor and said switch, thermostatic means for controlling the operation of the starting motor, means for supplying cooling liquid to the system, and means controlled by the pressure of the cooling liquid, for controlling the operation of the starting motor, to operate said connection to open and close the switch.
10. In a refrigerating system, the combination of a compressor, a motor for operating the compressor, a switch for controlling said motor, a starting motor, an operative connection between the starting motor and said switch, thermostatic means for controlling the operation of the starting motor, means for supplying cooling liquid to the system, a valve for the liquid, operated by the starting motor, and means controlled by the pressure of the cooling liquid, for controlling the operation of the starting motor to operate said connection to open and close the switch.
11. In a refrigerating system, the combination of a compressor, a motor for operating the compressor, a switch for controlling said motor, a starting motor, an operative connection between the starting motor and said switch, means for supplying cooling liquid to the system, and means controlled by the pressure of the cooling liquid, for controlling the operation of the starting motor to operate said connection to open the switch responsively to a deficiency in the liquid supply and to automatically close the switch upon restoration of the pressure.
12. In a refrigerating system, the combination of a compressor, a motor for operating the compressor, a switch for controlling said motor, a starting motor, an operative connection between the starting motor and said switch, thermostatic means for controlling the starting motor, means for supplying cooling liquid to the system, and means controlled by the pressure of the cooling liquid, for controlling the operation of the starting motor.
13. In a refrigerating system, the combination of a compressor, a motor for operating the compressor, a switch for controlling said motor, a starting motor, an operative connection between the starting motor and the switch, a valve for controlling the supply of cooling liquid to the system, a connection for operating said valve operated by the starting motor, automatic means for controlling the operation of the starting motor, and means controlled by the pressure of the cooling liquid for controlling the operation of the starting motor.
14. In a refrigerating system, the combination of a compressor, a motor for operating the compressor, a switch for controlling said motor, a starting motor, an operative connection between the starting motor and the switch, a valve for controlling the supply of cooling liquid to the system, a connection for operating said valve, operated by the starting motor, means for controlling the operation of the starting motor for starting and stopping cycles and means controlled by the pressure of the cooling liquid for controlling the operation of the starting motor to open and close said switch.
15. In a refrigerating system, the combination of a compressor, a motor for operating the compressor, a switch for controlling said motor, a starting motor, an operative connection between the starting motor and the switch, a valve for controlling the supply of cooling liquid to the system, a connection for operating said valve, operated by the starting motor, means for controlling the operation of the starting motor for starting and stopping, and means controlled by the pressure of the cooling liquid for controlling the operation of the starting motor to open said switch when the liquid-supply is deficient and to automatically close the switch upon restoration of pressure.
16. In a refrigerating system, the combination of a compressor, a motor for operating the compressor, a switch for controlling said motor, a starting motor, a shaft driven by said starting motor, an operative connection between the shaft and the switch comprising a cam, a valve for controlling the supply of cooling liquid to the system, a cam on said shaft for operating said valve, thermostatic means for controlling the operation of the starting motor, and means controlled by the pressure of the cooling liquid for controlling the operation of the starting motor.
17. In a refrigerating system, the combination of a compressor, a motor for operating the compressor, a switch for controlling the operation of said motor, a starting mo-

tor, an operative connection between the starting motor and said switch, a controller operated by the starting motor, controlling means for the starting motor connected to said controller, and comprising a switch connected to said controller and pressure-controlled means for operating the latter switch.

18. In a refrigerating system, the combination of a compressor, a motor for operating the compressor, a switch for controlling the operation of said motor, a starting motor, an operative connection between the starting motor and said switch, a controller operated by the starting motor, thermostatic controlling means for the starting motor, connected to said controller, said means comprising a switch connected to the controller, and pressure-controlled means for operating the latter switch.

19. In a refrigerating system, the combination of a compressor, a motor for operating the compressor, a switch for controlling the operation of said motor, a starting motor, an operative connection between the starting motor and said switch, a controller operated by the starting motor, thermostatic controlling means connected to said controller, said means comprising a switch connected to said controller, a valve operated by the starting motor, for supplying liquid to the system, and controlling means for the latter switch conjointly controlled by the valve and the pressure of liquid.

20. In a refrigerating system, the combination of a compressor, a motor for operating the compressor, a switch for controlling the operation of said motor, a starting motor, a shaft operated by the starting motor, an operative connection between said shaft and said switch, a controller on said shaft, electrical connections for said controller, for controlling the operation of the starting motor, a cam on the controller, a switch operated by said cam, a circuit connected to said latter switch, a switch in said circuit, and pressure-controlled means for operating said last mentioned switch.

21. In a refrigerating system, the combination of a compressor, a motor for operating the compressor, a switch for controlling the operation of said motor, a starting motor, a shaft operated by the starting motor, means on the shaft for operating said switch, a valve for controlling the supply of cooling liquid, means on said shaft for operating said valve, a circuit controller, means for controlling the operation of the starting motor comprising a switch, means for operating said latter switch conjointly controlled by said valve and the pressure of liquid, a thermostat, and electrical connections between the controller and the thermostat.

22. In a refrigerating system, the combi-

nation of a compressor, a motor for operating the compressor, a spring-closed switch for controlling the operation of said motor, a starting motor, a shaft operated by the starting motor, a cam on the shaft for operating said switch, a valve for controlling the supply of cooling liquid, means on said shaft for operating said valve, a circuit controller, means for controlling the operation of the starting motor comprising a switch, means for operating said latter switch, conjointly controlled by said valve and the pressure of liquid, a thermostat, and electrical connections between the controller and the thermostat.

23. In a refrigerating system, the combination of a compressor, a motor for operating the compressor, a switch for controlling the operation of said motor, a starting motor, a shaft operated by the starting motor, means on the shaft for operating said switch, a valve for controlling the supply of cooling liquid, means on said shaft for operating said valve, a controller, controlling means for the starting motor comprising a pair of switches, means for operating one of said latter switches, conjointly controlled by said valve and the pressure of liquid, means on the controller for operating the other of said pair of switches, a thermostat, and electrical connections between the controller and the thermostat.

24. In a refrigerating system, the combination of a compressor, a motor for operating the compressor, a switch for controlling the operation of said motor, a starting motor, a shaft operated by the starting motor, means on the shaft for operating said switch, a valve for controlling the supply of cooling liquid, means on said shaft for operating said valve, a controller, controlling means for the starting motor comprising a switch, a plunger operated by pressure of the liquid, connections for operating said latter switch, operable by said valve and the plunger, a thermostat and electrical connections between the controller and the thermostat.

25. In a refrigerating system, the combination of a compressor, a motor for operating the compressor, a switch for controlling the operation of said motor, a starting motor, a shaft operated by the starting motor, means on the shaft for operating said switch, a valve for controlling the supply of cooling liquid, means on said shaft for operating said valve, a circuit-controller operated by said shaft and means for controlling the starting motor comprising a switch operated by the controller and a switch conjointly controlled by said valve and the pressure of liquid.

26. In a refrigerating system, the combination of a compressor, a motor for operating the compressor, a switch for controlling the operation of said motor, a starting motor,

a shaft operated by the starting motor, means on the shaft for operating said switch, a valve for controlling the supply of cooling liquid, means on said shaft for operating 5 said valve, a circuit controller, on said shaft, and means for controlling the operation of the starting motor comprising a switch op- erated by the controller and a switch operable by said valve and the pressure of said liquid, a thermostat and electrical connections between the controller and the thermostat. 10

CHARLES C. HANSEN.

Copies of this patent may be obtained for five cents each, by addressing the "Commissioner of Patents, Washington, D. C."
